UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIO BROADCAST SELECTING AND DISTRIBUTING SYSTEM.

Application filed February 29, 1924. Serial No. 695,991.

My invention relates to systems of radio broadcast distribution, and has for its object to enable the subscribers in an organized system to select individually the stations 5 from which they desire to receive, while concentrating all the complicated apparatus necessary for such selection at one or more central points, thus reducing the receiving apparatus at the subscribers' stations to a 10 minimum. The present invention is of the nature of an improvement over that described and claimed in my prior applications filed February 9, 1924, Serial Nos. 691,820, 691,821, and 691,822.

15 The problem presented is solved in the present case as follows: Modulated waves from a distant station are received, amplified, and distributed to the subscribers from a central station, using wired circuits, preferably existing telephone lines. The apparatus at the central station is adapted to receive waves at any frequency desired, to transform said frequency and to convey the 20 modulations over the subscribers' lines at one standard frequency, made low enough for efficiency of transmission, while remaining super-audio. To effect this frequency transformation, the heterodyne principle is employed, providing local oscillators at the central station, and combining their outputs 25 with incoming waves in such manner as to produce a beat wave, which is then delivered to the subscribers' lines after detection, in the form of unidirectional pulsating current. 30 Where there are several subscribers on one line, as on a telephone party line, it is desirable to adopt a corresponding number of standard beat frequencies, which may be for example 25kc, 37kc, and 53kc. Distribution to the No. 1 subscribers on all party lines 35 would then be on say, 25kc, distribution to No. 2 subscribers would be on 37kc, distribution to No. 3 subscribers on 53kc, and so on.

40 I shall illustrate and describe herein very simple apparatus for carrying this invention into effect, with the understanding that instead of the manual switching apparatus shown, automatic apparatus, or so-called semi-automatic, may be employed, and that 45 I consider them as a part of my invention.

45 My invention is illustrated as to one form of embodiment in the accompanying drawings, in which—

50 Fig. 1 is a simplified diagram showing the 55 essential elements of the system.

Figs. 2 and 3 are detailed diagrams showing modes of coupling to the antenna and to the oscillator circuits respectively.

Fig. 4 is a diagram showing the same elements as Fig. 1, but with more detail.

Fig. 5 is a detail showing one manner in which the main tuning condenser and the selector switches for antenna and oscillator are coupled mechanically for conjoint selective operation.

Fig. 6 is a detail of the local signalling circuits at the central station, with the main or B battery bridged.

Fig. 7 shows the telephone switchboard with line terminals and one cord circuit, and should be read together with Fig. 4.

Referring to Fig. 1, C represents in general a central station and S the subscriber's station. At the central station, 1, 2 and 3 are antenna circuits broadly tuned for three different bands of frequencies, not overlapping. 4, 5 and 6 are three separate couplers having their secondaries connected in series in the circuit 7—8, which also includes a load coil 9 and one of a series of oscillator 75 couplers, as to the secondary winding thereof, 10, 11 and 12. 13, 14 and 15 represent the oscillators, each of which is tuned and adjusted to produce alternations or oscillations at a particular frequency only. AS' 80 is a switch by which the circuit 8 may be connected to any one of the secondary coils of the couplers 10, 11, 12. AC is a tuning condenser which together with the inductance of the several coils 4, 5, 6, 9 and 10, 85 renders the circuit 7—8 resonant or in tune with the frequency it is desired to receive. From opposite sides of the condenser AC wires 16 and 17 pass respectively to the grid 90 21 and the filament 20 of the detector tube DT. Wire 16 includes the usual grid condenser 19, and a grid leak 18. The filament battery is shown at 23^a and the plate battery at 23^b. From the latter wire 24 extends to the subscriber's station S, the return 100 wire 25 connecting with the filament 20 and the wire 17.

The operation of the system thus outlined is as follows: A subscriber desiring a particular station, calls up the radio operator, 105 who thereupon adjusts the condenser AC so as to tune the circuit 7—8 to the wave length of that station, and also adjusts the switch AS' so as to connect the proper oscillator coupling 10, 11 or 12, whereby to impose a 110

heterodyning frequency on the circuit 7-8 that with the frequency received from the antenna 1, 2 or 3, as determined by the tuning of the circuit, will produce a suitable 5 beat frequency in the circuit 16-17. This of course results from the imposition of the two relatively high frequencies on the circuit 7-16, 8-17, which includes the grid 10 21 and the filament return. The plate circuit 15 of the detector tube DT is connected directly to the subscriber's line, which is thus really a part of the plate circuit, a high potential pulsating current being produced in the line, to which the subscribers' receivers 20 are made to respond. It is to be particularly noted that with the arrangement shown in Fig. 1 all tubes, complicated tuning devices, antenna circuits, oscillators, and batteries are at the central station, and there is 25 nothing at the subscriber's station by way of apparatus except his simple broadcast receiving instrument and a phone condenser if desired.

Fig. 2 shows one antenna circuit, 1, with 25 a common primary 1^a and a plurality of secondaries 1^b, leading to the different circuits 7-8 in the exchange. Fig. 3 shows a similar arrangement of the oscillator circuit 13 and the coupler 10, one primary 10^a being 30 employed and a number of secondaries 10^b.

Referring to Fig. 4, which is to be read together with Figs. 7, 1, 2 and 3 are the antenna circuits, 4, 5, and 6 the couplers, but instead of having these all in series in the circuit 7-8, they are adapted to be connected thereto singly and selectively by the double pole switch AS. The oscillator circuits 13, 14, 15 are connected as before through the couplers 10, 11, 12 by means of the selective 40 switch AS'. The circuit 7-8 terminates in a plug P, the arrangement of the tube DT, the batteries 23^a and 23^b, and associated parts being the same as in Fig. 1. By means of the plug P the tube with its antenna switches 45 and oscillator connections can be connected through jacks J with any of the lines having radio service in the exchange.

In Fig. 5 I have shown the condenser AC, and the two double pole switches AS and 50 AS' all coupled together on a common shift, by means of which the condenser may be set to the particular station called for, the switch AS may be set to the contacts of the coupling of the antenna circuit 1, 2 or 3, which includes the frequency of the desired 55 station; and finally the switch AS' is thereby set for the oscillator whose frequency combined with that for which the condenser AC is adjusted, will produce the constant or 60 standard frequency beat wave which is to be put on the subscriber's line. Since the parts connected to circuit 16-17, which is the grid circuit of the detector DT are all local at the central station, and their constants 65 may be determined and fixed, I am

able to make the combined operation of the condenser AC and the two switches accurate and exact. In order to compensate for possible slight variations in the antenna circuits or in the oscillator circuits, which would require slight overthrow one way or the other in turning condenser AC, I may give the contacts of the switches AS and AS' more width than I have shown in the drawing, making these contacts if desired as arcs. Various other changes may be made, without departing from the principles involved, which is that of conjoint action, by means of which the tuning and connection of the two heterodyning sources are accomplished at 70 the same time and automatically. In connection with this, it should be stated that instead of using a manually operated cord circuit with a terminal plug P, I may use any desired form of automatic selector; and 75 in place of using a manual knob for turning the condenser AC and with it the arms of the switches AS and AS'. I may use step by step mechanism controlled from a distance, either by the operator or by the subscriber 80 who desires to receive from a particular station. In either case, a suitable dial or impulse sender would be employed, or the equivalent, to turn a ratchet wheel attached 85 in place of the knob to the end of the shaft 90 of the condenser AC in Fig. 5.

In order that the radio operator may have supervision and control over the connection of the cord circuit and plug P, with any line, I provide the cord with keys K-K'. The key K is a listening key, by means of which the operator can connect her telephone across the cord and line, and the key K' is a ringing key whereby the operator may connect a ringing generator to the subscriber's line and call him in the usual way or by means of any suitable and desired ringing device with which his station may be provided. In order that the telephone operators may know that a line is connected 100 for radio, and in order that the line relay LR (see Fig. 7) may be cut off while the line is in use, I provide a battery connection B (Fig. 4) which may be either the main telephone battery shown in Fig. 7, or a special battery, and a tone test BT of known type. When the plug P is inserted in a jack J, the tip sleeve and ring contacts, p, p' and p² come into conjunction with the jack contacts j, j', and j², the first of which goes to the tip side of line 24, the second to the sleeve side of line 25, and the third to the wire circuit 26 leading to the cut-off relay CO, shown in Fig. 7, and to the test thimbles j² of all the multiple jacks of the same line. The tone test BT should be a characteristic "radio" tone test, so that the operators will 110 all know, when they get that test, that they are at liberty to plug in on the telephone switchboard and ring the wanted subscriber, 120 125 130

which can be done without stopping the radiophone receiving. For enabling the subscriber to call in, a supervisory signal may be provided as in Fig. 6, to which the 5 tone test BT must be added. In this case, allowance must be made for battery current in the line of sufficient amperes to work the supervisory relay SR, which controls the supervisory lamp SL. In Fig. 6, I have shown 10 the battery 23^b, that is to say, the plate battery, as bridged across the cord conductors 16^a and 17^a, with radio and audio choke coils 23^c, in the battery bridge. This is ordinary 15 telephone practice, in so far as the bridging of the battery is concerned and for audio purposes is well known in the art, but I believe is novel and original with me in connection with a detector circuit, or for the passage of super-audio currents. The action 20 in the plate circuit would be to cause oscillations to pass through the main line to the subscriber, due to variance of potentials which cannot produce any variance in the current flow in the battery bridge, owing 25 to the choke coils 23^c.

The arrangement of the plate battery 23^b in Fig. 4 is in series, and the operator's listening key K may be designed to put her 30 headphone in series. The arrangement of the battery 23^b in Fig. 6 is in bridge or parallel, and in this case the operator's headphone may be in parallel, or may be connected in series as before.

All the switchboard circuits shown in 35 Figs. 4, 6 and 7 as well as the subscriber's telephone circuit in Fig. 7, are standard Western Electric No. 1 circuits. Any other standard and suitable telephone circuits may be substituted, without departing from the 40 scope of the invention.

In Fig. 7 I have shown two subscribers' receiving instruments, one TR being a headphone with a variable condenser SC bridged across it in a cord circuit which terminates 45 in a plug P² adapted to cooperate with a jack J² connected to the line of the subscriber's station S; and the other HR, being a cabinet instrument containing a wooden horn or amplifier h, and phone condenser SC if desired, and amplifying apparatus, consisting either of tubes or other means which will enable the modulated waves received from central to be detected, amplified and propagated through the horn h.

50 In operation, the subscriber in this system desiring to receive modulated radio waves from a particular station, calls up the radio operator at the central office, which he may do by moving the switchhook of his telephone up and down, to flash the signal lamp controlled by his line relay LR on the telephone switchboard. This signal lamp may have a duplicate included in its own circuit and located upon the radio switchboard if 55 desired, but for simplicity one signal lamp

is sufficient. The telephone operator perceiving the lamp to flash, recognizes a radio signal and by means of suitable order circuits not shown, gives the number of the line to the radio operator, who thereupon 70 plugs in with a plug as P in Fig. 4, and by means of K connects her telephone and ascertains the subscriber's wishes. The stations which may be selected by the subscriber may be designated either by numbers or by 75 their call letters. In either case, the condenser dial AC if such be used, may be graduated and marked with the letters and numbers of the said stations, and the operator by setting the condenser to the desired 80 station will thereby automatically tune the circuit 16-17, connect the proper antenna circuit 1, 2 or 3, and the proper oscillator 13, 14 or 15 to produce standard beat wave for which the subscribers' lines and receiving 85 circuits are adapted. By listening in on the plate circuit through the key K, the operator may sharpen the tuning, if desired. With the arrangement shown in Fig. 6 after the foregoing connections have been made, the 90 subscriber may recall the operator by the flashing of supervisory lamp SL, it being supposed that the resistance of his receiver bridged across the line is suitable for this purpose. Recalls are for the purpose of 95 changing the station from which program is being received. If necessary to prevent undue shunting of the modulated waves sent out over the conductors 24-25, a radio choke coil may be inserted in the telephone 100 branch at the station S. I have not considered it necessary to show this, but I wish it understood that such expedients as choke coils, condensers and the like, which are known in the art, are to be applied wherever 105 needed in the practical use of this system.

I claim:

1. A broadcasting system comprising the following instrumentalities: subscribers' stations and a central station containing receiving apparatus with a tunable input circuit for selection of radio transmitting stations, means for supplying heterodyning oscillations to said circuit, a wire line extending to a subscriber's station, and a detector at the 110 central station having its grid circuit connected to said tuned input circuit, and its plate circuit extended directly to said line, together with suitable receiving means at the subscriber's station responsive to current 115 undulations in said plate circuit.

2. A broadcasting system comprising the following instrumentalities: subscribers' stations and a central station and wire lines interconnecting them, switching terminals 120 for said lines at the central station, and radio distributing means also at the central station comprising switching terminals 125 adapted to cooperate with the line terminal, a thermionic tube having its plate circuit 130

connected to said switching terminals together with a suitable source of plate current, and a signal device in said plate circuit with means at a subscriber's station responsive to current changes in the plate circuit and adapted to control said signal.

3. A broadcasting system comprising the following instrumentalities: subscribers' stations and a central station and wire lines interconnecting them, switching terminals for said lines at the central station, and radio distributing means also at the central station comprising switching terminals adapted to cooperate with the line terminals, a thermionic tube having its plate circuit connected to said switching terminals together with a suitable source of plate current bridged across the plate circuit, and thereby bridged across the subscriber's line, when switched for receiving, a signal in series with and on the line circuit side of said battery bridge

and means at a subscriber's station adapted to produce changes in said line circuit and plate circuit current and thereby operate said signal.

25

4. In a radio broadcasting system, a central distributing station, subscribers' stations connected therewith by wire lines, radio receiving apparatus at said central station with means for selecting different primary transmitting stations, means for supplying amplifying current, a detector tube connected to receive said waves with the amplifying current, and means to extend the plate circuit of said tube to a wire line thence to the subscriber's station with means at said station responsive to modulated unidirectional pulsating current impulses in said plate circuit and line.
